US00D439126S

(12) **United States Design Patent**
Gohman

(10) Patent No.: **US D439,126 S**
(45) Date of Patent: **** Mar. 20, 2001**

(54) **ROOFING MATERIAL REMOVAL TOOL**(75) Inventor: **Bret A. Gohman**, South Haven, MN (US)(73) Assignee: **Malco Products, Inc.**, Annandale, MN (US)(**) Term: **14 Years**(21) Appl. No.: **29/123,646**(22) Filed: **May 23, 2000****Related U.S. Application Data**

(62) Division of application No. 09/176,975, filed on Oct. 22, 1998, now abandoned.

(51) **LOC (7) Cl.** **08-05**(52) **U.S. Cl.** **D8/89**(58) **Field of Search** **D8/14, 45, 88, D8/89; D32/46; 30/169, 171, 170, 172; 254/25, 131; 294/49, 55, 57**(56) **References Cited****U.S. PATENT DOCUMENTS**
